UNITED STATES PATENT OFFICE.

DANIEL B. CAVE, OF BEATRICE, NEBRASKA, ASSIGNOR OF ONE-THIRD TO MICHAEL A. CUNNINGHAM AND ONE-THIRD TO LLOYD CROCKER, BOTH OF BEATRICE, NEBRASKA.

CENTRIFUGAL SEPARATOR AND AMALGAMATOR.

1,053,785.

Specification of Letters Patent. Patented Feb. 18, 1913.

Application filed June 13, 1912. Serial No. 703,528.

To all whom it may concern:

Be it known that I, DANIEL B. CAVE, a citizen of the United States, residing at Beatrice, in the county of Gage and State of Nebraska, have invented certain new and useful Improvements in Centrifugal Separators and Amalgamators; and I do declare the following to be a full, clear, and exact description of the invention, such as will enable others skilled in the art to which it appertains to make and use the same.

This invention relates to separators, and more especially to those using mercury for removing the precious metals from the ore; and the object of the same is to combine the amalgamating principle with a centrifugal separator so that the force of centrifugal action is employed to pass the wet mass or slime outward over a series of annular pans, during which passage the precious metals are extracted by and later may be cleaned from the pans. This and other objects are carried out by building and operating the machine in the manner hereinafter more fully described and claimed, and as shown in the drawings wherein—

Figure 1 is a central vertical section; Fig. 2 is a plan view.

In the drawings the numeral 1 designates a suitable framework in which in a step bearing 2 is mounted an upright shaft, preferably by means of ball bearings 3 as shown, its upper end being journaled as at 4 in the framework in any suitable manner. Around the upper end of the main shaft 5 is a sleeve 6, and around the sleeve in turn is a funnel-shaped hopper 7 into which the slime is fed in any suitable manner. Surrounding the entire machine hereinafter described is a large receptacle 8 whose inclined bottom 9 passes across the shaft as shown, and leads to an outlet 10 through which the waste products are conducted in a manner which will be explained below.

Nested upon each other around the main shaft 5 are a number of tubes 11, 12 and 13 respectively carrying sprocket pinions 14, 15 and 16 at their lower ends resting upon each other and the lowermost resting upon another pinion 17 which is fast on the shaft 5; and these pinions are driven at different speeds in any suitable manner and from any suitable source. As illustrating the same I have shown a driving shaft 18 having sprocket gears 19, 20, 21, 22 which increase

in size in the order shown, and each gear is connected by a chain 23 with the pinion respectively opposite it, so that when the shaft 18 is rotated the various pinions will be turned at different speeds for a purpose which will appear below. As a serviceable means for driving the shaft 18, it may be provided with a disk 24 against which a power wheel 25 may contact at any suitable point from the center of the disk, according as said wheel 25 is adjusted by means of a fork 26 on a lever 27, the hub 28 of the power wheel being splined on a power shaft 29 as will be clear. However I do not wish to be limited to the exact means for driving the various sprocket pinions at different speeds.

Fixed upon the main shaft 5 is a pan 30 and respectively upon the upper ends of the tubes or sleeves 11, 12 and 13, are spiders 31, 32 and 33 increasing in size from the uppermost to the lowermost as shown, and these spiders carry annular pans which are duplicates of the pan 30 and of each other excepting as to their size, so that a description of one will suffice for all. Its body 34 is flat and provided with an upstanding flange 35 around its inner edge, its outer edge or rim being bent upward and inward into a flange 36, beneath which may depend another flange or skirt 37. Disposed within the pan near its rim is an annular baffle 38 which is preferably notched around its lower and outer edge as at 39 so as to produce occasional fingers 40 by which it is supported upon the body 34 of the pan, while its inner edge is elevated considerably above the upper face of said body because of the fact that the body of the baffle stands oblique as shown. Also mounted within the pan is an upright shield 41 similarly notched around its lower edge as at 42 to produce fingers 43 by which it is supported upon the pan, its upper edge being turned inward into a spillway 44 and standing above the upper edge of the rim 36 of the next smaller pan so as to produce an opening between them for a purpose yet to appear. Such is the construction of each pan and would be the construction of more pans than shown in the drawings if the machine were amplified in size; and the innermost pan follows the same construction in substance, excepting that its inner flange 45 here constitutes the hub of the pan 30 which is mounted fast

upon the main shaft 5, and the mouth of the feed hopper 7 delivers the material onto this inner pan around its hub or flange 45.

In practice mercury to the required amount is poured into the pans, and when these are revolved at the proper rate of speed centrifugal action causes the mercury to flow outward over their bottoms against their rims 36 where it forms a substantially upright wall. The slime which is to be treated is fed into it through the hopper 7 by means not necessary to illustrate, and falls into the smaller pan which is rotating at a given speed; the centrifugal action causes it to flow outward over the body of the pan and accumulate under its rim, passing meanwhile through the notches 39 in the baffle 38. After the material has accumulated to a sufficient extent it will flow over the upper edge of the rim and, passing under the inturned upper edge of the spillway 41 in the next pan toward the periphery, it will flow down the inner face of said spillway, under its lower edge and through its notches, where the operation for this pan is repeated like that for the first. During this movement of the slime the previous metals are brought into direct contact with the mercury and amalgamation is produced, the values being retained while the baser materials are permitted to flow over the spillway and are finally carried to the dump or waste. The reason why this pan is rotated at a slower speed than the innermost will now be apparent, for if all the pans were mounted rigidly on the shaft they would revolve around it in the same period of time and any point in the rim of a larger pan would have to move more rapidly than it would in a smaller pan in order to make the complete circuit around the shaft, and therefore the centrifugal action in the larger pan would be greater. With the construction shown and described, as the material overflows the rim of a smaller pan and drops onto the body of the next larger pan, it is subjected to the same centrifugal action and to practically the same centrifugal force, and the separating action is repeated in the manner just described. So also, after the material passes out of the second pan into the third, and thence on into the fourth and throughout the series if more pans than shown be employed; and finally the waste products flow over from the outermost pan and are trapped under the inturned edge 50 of the receptacle 8, wherein they gather on the bottom 9 thereof and flow out through the outlet 10. From time to time the precious metals are removed by means forming no part of the present invention.

The parts of this machine are of the desired sizes, shapes, proportions, and materials; and changes in details may be made

without departing from the principle of the invention.

What is claimed as new is:—

1. In a centrifugal separator, the combination with a series of circular pans disposed one above and overlapping another and decreasing in size toward the top of the series, means for supplying material to the smallest pan, and means for conducting the waste products from the largest pan; of mechanism for rotating the pans independently at such speeds that the inner pan will complete a rotation in less time than any other.

2. In a centrifugal separator, the combination with a series of pans disposed one above and overlapping another and decreasing in size toward the top of the series, means for supplying material to the smallest pan, and means for conducting the waste products from the largest pan; of mechanism for rotating the series so that the peripheries of all the pans move at the same speed.

3. In a centrifugal separator, the combination with a series of concentric circular pans disposed one above and overlapping another and decreasing in size toward the top of the series, means for supplying material to the smallest pan, and means for conducting the waste products from the largest pan; of an upright shaft on which the smallest pan is mounted, a series of nested tubes around said shaft, spiders independently secured to the upper ends of said tubes and each carrying a pan, and mechanism for rotating the shaft and the various tubes so that the peripheries of all the pans will move at the same speed.

4. In a centrifugal separator, the combination with a series of concentric circular pans disposed one above and overlapping another and decreasing in size toward the top of the series, means for supplying material to the smallest pan, and means for conducting the waste products from the largest pan; of an upright shaft on which the smallest pan is mounted, a series of nested tubes around said shaft, spiders independently secured to the upper ends of said tubes and each carrying a pan, a series of pinions secured respectively to the lower ends of said tubes, and a series of driving gears respectively connected with said pinions, the wheels in one of said series increasing in size from one end of the series to the other whereby the peripheries of all the pans are caused to move at the same speed.

5. In a machine of the class described, the combination with a series of concentric circular pans disposed one above and overlapping another and decreasing in size toward the top of the series, means for supplying material to the uppermost pan and

removing the waste products from the series, and means in each pan for extracting the precious metals; of mechanism for rotating the pans independently at different speeds and in the same direction.

6. In a machine of the class described, the combination with a series of circular pans disposed one above and overlapping another and decreasing in size toward the top of the series, means for supplying material to the uppermost pan and removing the waste products from the series, and means in each pan for extracting the precious metals; of mechanism for rotating the pans independently at such speeds that the inner pan will complete a rotation in less time than any other.

7. In a machine of the class described, the combination with a series of circular pans disposed one above and overlapping another and decreasing in size toward the top of the series, means for supplying material to the uppermost pan and removing the waste products from the series, and means in each pan for extracting the precious metals; of mechanism for rotating the series so that the peripheries of all the pans move at the same speed.

8. In a centrifugal separator, the combination with a plurality of concentric circular pans disposed one above and overlapping the other and the uppermost being of smaller diameter, each pan having a rim rising from its body and bent inward; of means for supplying material to the smallest pan, and mechanism for rotating the pans so that their peripheries shall move at approximately the same speed.

9. In a centrifugal separator, the combination with a plurality of circular pans disposed one above and overlapping the other and the uppermost being of smaller diameter, each pan having a rim rising from its body and bent inward, and in each pan a shield rising from its body and bent inward

over the rim of the next smaller pan and constituting a spillway; of means for supplying material to the smallest pan, and mechanism for rotating the pans so that their peripheries shall move at approximately the same speed.

10. In a machine of the class described, the combination with a series of pans disposed one above and overlapping the other and the uppermost being of smaller diameter, each pan having a rim rising from its body and bent inward, and in each pan a shield rising from its body and bent inward over the rim of the next smaller pan and constituting a spillway and an annular member in each pan having its lower edge notched and the interposed fingers between said notches resting on the body of the pan; of means for supplying material to the smallest pan, and mechanism for rotating the pans so that their peripheries shall move at approximately the same speed.

11. In a machine of the class described, the combination with a plurality of concentric annular pans disposed one above and overlapping the other and the uppermost being of smaller diameter, each pan having a shield rising from its body and bent inward over the rim of the next smaller pan and constituting a spillway, and an obliquely disposed annular member in each pan, said shield and member having their lower edges notched and the interposed fingers between said notches resting on the body of the pan; of means for supplying material to the smallest pan, and mechanism for rotating the pans so that their peripheries shall move at approximately the same speed.

In testimony whereof I have hereunto set my hand in presence of two subscribing witnesses.

DANIEL B. CAVE.
